UNITED STATES PATENT OFFICE.

EDWIN HUGHES, OF LAMBETH, ASSIGNOR TO PHILIP WEBLEY, THOMAS WILLIAM WEBLEY, AND HENRY WEBLEY, OF BIRMINGHAM, ENGLAND.

IMPROVEMENT IN BREECH-LOADING FIRE-ARMS.

Specification forming part of Letters Patent No. 177,642, dated May 23, 1876; application filed November 5, 1875.

To all whom it may concern:

Be it known that I, EDWIN HUGHES, of 36 Brook street, Kennington Road, Lambeth, in the county of Surry, England, have invented certain Improvements in Breech-Loading Fowling-Pieces and Rifles, of which the following is a specification:

This invention has for its object improvements in breech-loading fowling-pieces and rifles, and is applicable to arms in which the barrels are mounted on an axis, so that for loading the muzzles may be depressed and the open breeches raised above the breech-plate to receive the cartridges. The hand-lever employed to withdraw the bolt or bolts and release the barrels is arranged to work on an axis between the locks and on or in a line with the axis of the tumblers, or nearly so. The tumblers have a limb or arm projecting from their side to come in front of the hand-lever, and on the hand-lever is a corresponding projection, so that by the same operation of the hand-lever which unlocks the barrels both hammers are raised to full cock, and in consequence of the tumblers and the hand-lever moving around the same center the thrust upon the tumblers is direct, and an easy action is obtained, and but little power has to be applied beyond that requisite to overcome the main springs connected with the tumblers and the spring of the hand-lever.

The stem of the bolt employed for locking the barrels is bent upward to carry it above the working parts of the locks, and bring it into position to engage with a projection on the hand-lever, so that the turning of the hand-lever shall withdraw the locking-bolts at the same time that it raises the hammers to full cock.

The axis on which the hand-lever turns may be hollow, and receive into it the ends of the axis of the tumblers, one on either side. The tumbler axes pass through the lock-plates, and receive outside hammers of the ordinary form, thus making a self-cocking gun to strike the nipples outside, whereas heretofore self-cocking guns have been made with strikers to strike inside, and consequently fouling has accumulated in the lock-work.

The gun can be made with the ordinary

back-action locks, if required, with a projection on the tumbler to receive the pressure of the lever that releases the bolt of the gun, the lever working in a line with the axis of the tumbler, as before described, or the gun can be made with all the lock-work on the trigger-plate, and imitation locks, with the tumbler axis passing through the lock-plate to receive the hammers, or it can, if desired, be made to strike inside the lock-plate in the same manner as ordinary self-cocking guns are now made.

In order that my said invention may be most fully understood, and readily carried into effect, I will proceed to describe the drawings hereunto annexed.

Figure 1 is a longitudinal section of a breech-loading fowling-piece, constructed according to my invention. Fig. 2 is a plan, partly in section, of the breech-piece and the trigger-plate, and many of the parts in connection therewith, but without the barrels, stock, trigger-guard, and hammers, which, however, are all indicated in Fig. 1. Fig. 3 is a side view, and Fig. 4 is a plan, of the breech-piece. Fig. 5 is a side view, and Fig. 6 is a plan, of the trigger-plate.

The trigger-plate has formed upon it a central lump or projection, a^1 , in which is a slot, through which the head of the hand-lever passes. A side view of the hand-lever is shown at Fig. 7, and a front view at Fig. 8. The hand-lever works upon a hollow steel pin inserted into the hole b^1 in the lever, and into corresponding holes in the two sides of the slotted lump a^1 . The trigger-plate and the hinder part of the lump are also slotted at a^2 to receive the triggers shown at Fig. 9. The hole a^{1x} in the lump a^1 receives the pin, on which the triggers turn. a^3 is a hole to receive the screw, by which the trigger-spring is fixed. This spring, which is clearly seen in Fig. 1, passes between the triggers. It is slit longitudinally, so that its two limbs may operate independently on the two triggers, and the free end of each limb turns outward at a right angle, and enters a hole, c , drilled in the side of the trigger.

a^4 a^4 are holes to receive screws, by which two standards are fixed to the trigger-plate. A side view of one of these standards is

shown at Fig. 10 and a plan at Fig. 11. The two standards are right and left, but otherwise similar. d' is a hole in the standard for the passage of the tumbler axis, for which the standard forms the outer bearing, the inner bearing being in the hollow axis of the hand-lever. A side view of one of the tumblers is shown at Fig. 12, and a front view at Fig. 13. The tumblers are right and left. $a^5 a^5$ are two studs screwed into the trigger-plate. The sear-pins pass through them into the lump a^1 . Fig. 14 is a side view, and Fig. 15 is a plan, of one of the sears. The sears are right and left. $a^6 a^6$ are recesses formed at the bottom of the grooves in the trigger-plate, which accommodate the sear-springs, one of which is clearly shown in Fig. 1. Projections on the under side of the sear-springs enter the recesses a^6 and the bends of the springs are housed beneath the studs $a^7 a^7$, which are screwed into the trigger-plate. The same studs also confine the mainsprings at one end, the other end in each case being connected with tumbler by a swivel, in the usual way. The bends of the mainsprings are received into another lump, a^8 , formed upon the trigger-plate. One of the mainsprings is clearly shown in Fig. 1. a^{1xx} is a tapped hole in the lump a^1 to receive the screw d , which passes through the tang of the breech-piece and the wooden stock, binding all firmly together. $a^9 a^9$ are holes receiving screws connecting the trigger-plate with the under side of the breech-piece, and a^{10} is a hole receiving a screw which connects the hinder end of the trigger-plate with the stock. On the top of the lump a^8 is fixed, by a screw, the spring e for the hand-lever. It is connected with the lever by a swivel.

When the hand-lever is forced forward, it carries round the tumblers with it, as arms $f' f'$ of the tumblers abut upon the sides of the notch or recess b^2 in the hand-lever. Thus the hammers g , which are fixed in the usual way upon the squares of the tumblers, are raised to full cock, and they are retained there by the sears until they are liberated by means of the triggers. At the same time that the hand-lever raises the hammers it draws back the locking-bolt, to release the barrels and allow the breeches to be opened.

Fig. 16 is a side view, Fig. 17 an end view, and Fig. 18 a plan, of the locking-bolt. The locking-bolt works in a passage cut for it in the breech-piece, and at h^1 it catches the locking-projection fixed on the under side of the barrels. The bolt also gives motion to the rotary lock i , which is a cylinder turning on a central stud fixed in the breech-piece. It has bayonet-grooves cut in it—one on either side. Projections on the under side of the barrels pass down into these grooves, and then the partial rotation of the rotary lock causes the projections to pass into recesses, from which they cannot escape until the rotary lock is again turned partly round. The rotary lock takes its motion from the locking-bolt by a pin upon it entering the oval recess h^2 . Fig. 19 shows the lock-plate, which, in the arrangement shown, carries none of the working parts, although the parts of the lock may be mounted upon the lock-plate without departing from my invention. In place of the mainsprings being arranged to pass to the back, as in back-action locks, they may be arranged to pass to the front, as in front-action locks, and lie within slots formed in the under side of the breech-piece, the plate which carries the lock-work being carried forward under the breech-piece to support the springs.

What I claim is—

1. The combination, substantially as herein-before set forth, of the locking-bolt bent upward at its rear end, the hammer-tumblers, and the hand-lever rocking vertically on an axis, substantially in line with the axes of the tumblers, and engaging with the bent portion of the locking-bolt, whereby the bolt may be withdrawn to allow the breech to be tilted, and the hammers are cocked by the direct action of the lever.

2. The combination of the hand-lever, the hollow pin upon which it works, and the hammer-tumblers having their axes inserted in said hollow pin, substantially as and for the purpose set forth.

EDWIN HUGHES.
